Primary Examiner — Mimosa De(57) **CLAIM**

The ornamental design for a zero gravity chair, as shown and described.

DESCRIPTION

FIG. 1 is a front perspective view of the zero gravity chair of the invention shown in an upright position;

FIG. 2 is a front perspective view of the zero gravity chair of the invention shown in a reclined position;

FIG. 3 is a top plan view of the chair of FIG. 2;

FIG. 4 is a top plan view of the chair of FIG. 1;

FIG. 5 is a side view of the chair of FIG. 2;

FIG. 6 is a side view of the chair of FIG. 1;

FIG. 7 is a rear view of the chair of FIG. 2;

FIG. 8 is a rear view of the chair of FIG. 1;

FIG. 9 is a front view of the chair of FIG. 2; and,

FIG. 10 is a front view of the chair of FIG. 1.
